INVENTOR

William R. Jeavons

BY H. T. Fisher ATTY

UNITED STATES PATENT OFFICE.

WILLIAM R. JEAVONS, OF CLEVELAND, OHIO.

DESIGN FOR A BOWL FOR HYDROCARBON-BURNERS.

SPECIFICATION forming part of Design No. 35,562, dated January 7, 1902.

Application filed December 4, 1901. Serial No. 84,708. Term of patent 7 years.

To all whom it may concern:

Be it known that I, WILLIAM R. JEAVONS, a citizen of the United States, residing at Cleveland, in the county of Cuyahoga and State of Ohio, have invented and produced a new and original Design for a Bowl for Hydrocarbon-Burners, of which the following is a specification, reference being had to the accompanying drawings, forming part thereof, and in which—

Figure 1 is a perspective elevation of the design, and Fig. 2 a cross-section thereof.

The design of bowl thus shown is rendered new and original in the art by reason, chiefly, of the peculiarity of the central portion thereof, which is characterized by a circular and

somewhat dome-shaped formation *a*, marked conspicuously by a tapered or converging surface *b* about its top. The trough *c* of the bowl is outside of and beneath this special elevation, which rises from about the inner edge of the trough and stands above the same.

What I claim is—

The design for a bowl for hydrocarbon-burners, substantially as shown and described.

Witness my hand to the foregoing specification this 23d day of November, 1901.

WILLIAM R. JEAVONS.

Witnesses:

R. B. MOSER,
H. E. MUDRA.
